UNITED STATES PATENT OFFICE.

WILLIAM A. JONES, OF WEST NEW BRIGHTON, NEW YORK, ASSIGNOR TO THE BAB-COCK & WILCOX COMPANY, OF BAYONNE, NEW JERSEY, A CORPORATION OF NEW JERSEY.

BOILER FURNACE.

Application filed June 16, 1923. Serial No. 645,779.

My invention relates to boiler furnaces and will be understood by reference to the accompanying drawings, in which Fig. 1 is a sectional side elevation of a boiler furnace embodying my invention; Fig. 2 is a plan view of the water boxes and the connections therefor; Fig. 3 is an elevation of the parts shown in Fig. 2; Fig. 4 is a partially vertical section through the stoker furnace chamber and showing the rear wall water box in elevation and the side water boxes in section; Fig. 5 is a detail front view of the rear wall water box, partly in section, and on a larger scale, than shown in Fig. 4; Fig. 6 is an end view of the box shown in Fig. 5; Fig. 7 is a sectional view on line 7—7 of Fig. 5; Fig. 8 is a view of a part of the rear wall water box and the rear bridge wall and shows the relation between the side water boxes and the rear water box; Fig. 9 is an end view of the part shown in Fig. 8; Fig. 10 is a sectional view through the left side water box and blast box of the stoker, and Fig. 11 is a sectional view of the lower member of the boiler pressure parts to which the water box connections are made.

Referring to the drawings, particularly Fig. 1, the numeral 10 designates the furnace chamber in which is placed a blast chain grate stoker 11. Above the furnace is a bank 12 of water tubes which are connected at their ends to water compartments 13 and 14. A superheater 15 is placed above the bank of water tubes, and in the path of the first and second passes of the gases from the furnace 10 as they are directed back and forth across the tubes 12 by the baffles shown. A steam and water drum 16 is connected with the water compartments 13 and 14 of the tubes and is supplied with water from the economizer through which the gases pass after having passed through the boiler. The furnace is provided with front and rear walls 18 and 19, respectively, and with side walls 19'.

For the purpose of protecting the side walls adjacent the chain grate of the stoker, and the rear bridge wall at the end of the stoker, water boxes are placed in these walls. In the illustrative embodiment, the rear wall is provided with a cylindrical water box 20 which extends across the rear of the stoker and slopes upwardly from right to left, as viewed in Fig. 4. This box

extends the entire length of the rear wall and its ends extend through the side walls of the furnace. At its lower end a tube seat 21 is formed by projecting the metal of the wall of the tube outwardly, as best shown in Fig. 5. By thus forming the tube seats, a sort of dome is produced which insures against the formation of steam pockets where the ends of the pipe connections are attached to the box. That is to say, the end of the connecting pipe does not extend below the tube seat in the box, as would be the case if a plain opening were made in the box wall and the pipe inserted therein.

A pipe 22 connects at one end with the box 20, and at its other end with a flanged elbow 23 which connects with a pipe 24. The pipe 24 is connected with the lower forward member 25 of the boiler pressure parts, which, in turn, are connected with the downtake water compartment 14 of the water tubes. The pipes 22 and 24 are placed outside of the furnace chamber and will, therefore, be kept relatively cool and will receive no heat from the surrounding atmosphere, so that the water within these pipes will be relatively dense and will contain substantially no steam. A second tube seat 26 is formed in the box 20, as shown in Fig. 5, and a bent pipe 27 connects the box 20 with the lower rear member 28 of the boiler pressure parts. The pipe 27 is inside the furnace so that it is exposed to the heat of the furnace and the water and steam in pipe 27 will, therefore, be at a higher temperature and less dense than the water in pipe 22. This arrangement causes the water to flow downwardly in pipe 22 to supply water to the box 20 at its lower end, and the water automatically circulates through the box and passes therefrom through the pipe 27 into the member 28 and thence to the uptake water compartment 13 of the boiler. Any steam which may be formed in the water box 20 before it reaches the outlet pipe 27 will tend to decrease further the density of the water in pipe 27 and will thereby further increase the velocity of the circulation. For reasons already given, there will be no tendency to form a steam pocket at the tube seat 26.

Pipe 27 is curved, as shown in Figs. 1 to 3, preferably so as to have a reverse bend with part of the bend at right-angles to the axes of the ends of the tubes. By reason

of its departure from a straight line between the tube seat 30 in member 28 and tube seat 26 in box 20, particularly if bent in the manner illustrated, pipe 27 is so flexible 5 that the lower boiler member 28 may move upward or downward, due to the expansion or contraction of the boiler pressure parts from variations in temperature, without overstraining pipe 27. The bending stress 10 in pipe 27, which is created by this movement, will be for any given part of the pipe, directly proportional to the distance of that part of the pipe from the straight line between the seats 30 and 26, and since the 15 ends of the pipe at 26 and 30 have their axes parallel, there will be no bending stress, although there will be at these points a relatively small direct longitudinal stress. This arrangement results in the greatest 20 stress in the pipe occurring where it will not tend to loosen the ends of the pipe in the tube seats. It is noted that the pipe 27 lies substantially in a single plane. The above principle is employed in the connections 25 formed by pipe 22, elbow 23 and pipe 24 between tube seat 21 in box 20, and tube seat 31 in the lower forward member 25 of the boiler, and this connection is, therefore, also very flexible. This pipe connection 30 does not lie in a single plane so that a certain torsional flexibility is also present. Water boxes 32 and 33 are provided in side walls 19' of the furnace chamber. The box 32 is placed in the left wall and the box 33 35 in the right side wall, as viewed from the front of the furnace. These boxes slope upward from the front toward the rear of the boiler, so that the steam which is formed therein will flow upward toward the rear. The boxes 32 and 33 pass under the bridge 40 wall box 20 and extend through the rear of the setting. They are provided with handholes and fittings therefor at their rear ends so that they may be inspected inside 45 throughout their length. These boxes are provided at their lower ends with pipe connections 34 for box 32, and with pipe connections 35 for the box 33 from the lower forward boiler pressure member 25. These 50 connections are exterior to the furnace and, being cool, are filled with dense water without steam. The seat 36 on box 32 and seat 37 on the box 33 are formed in the same manner as seats 21 and 26 on the box 20. These boxes 55 32 and 33 are connected by bent pipes 38 and 39, respectively, with the lower rear boiler pressure member 28, and are similar to pipe 27. These pipes are within the furnace and are exposed to the 60 heat thereof, so that steam will be generated in them and the water will be less dense than that within pipes 34 and 35, and the circulation will, therefore, be downward in pipes 34 and 35, and upward in pipes 38 and 39 65 in the manner heretofore described in con-

nection with the bridge wall box connections.

The box 20 is provided with handholes and fittings 40 and 41 are provided for these handholes, as shown in Fig. 4. By removing 70 these fittings it is possible to look through the box, and if it contains dirt or scale or other foreign matter, the same may be easily removed therefrom through the handholes. A blow-off connection 42 is provided at the 75 lower end of the box near the bottom and provides means for draining the box and for blowing out any muddy water which it might contain. An auxiliary drain pipe 50 (see Fig. 8) of small diameter and provided 80 with a valve is shown, and may be used when the boiler is in active service. The use of a large blow-off pipe instead of the auxiliary drain pipe would tend to rob the box of such a quantity of water that it 85 might be endangered. A handhole is provided at the rear of box 32, and a similar hole is also provided at the rear of box 33 and fittings 43 and 44, respectively, are applied to these openings. Similar handholes 90 and fittings 46 and 47 are provided near the forward ends of these boxes and may be removed for permitting observation throughout the length of the boxes. Drain connections 48 and 49 are provided on the sides 95 of these boxes near their lower forward ends and are similar to that used on the rear wall box 20.

In Fig. 11 is illustrated the manner in 100 which the tubes 27, 38 and 39 pass through the drip pan 50 below the pressure part 28. This drip pan is connected to the boiler setting parts, so that there may be relative movement between the parts 28 and 50. An opening for each tube is provided in the pan 105 50 and a thimble 51 inserted therein, so that the pan will not leak. The opening in the thimble 51 is large enough to permit the tube to move up and down therein. The flexible sealing plate 52 will also have suitable openings for the tube. In the boiler shown in the drawings the upper end of the uptake header of the boiler is supported in a fixed position. The side wall water box is also supported in a fixed position. When the temperature of the boiler and that of tube 39 are increased from atmospheric temperature to that of the hot water and the steam in the boiler, both the boiler 115 part and the pipe 39 increase in length. Since the upper end of the uptake header and the side wall box 32 are fixed there must be sufficient flexibility in the pipe 39 to accommodate the movement due to this increase in length.

With tube 39 of the shape shown a very moderate force tending to shorten the distance between its ends causes the tube to bend the necessary amount.

The principle employed with the tube 34 130

is the same as with 39. The connection 34 extends upward from the water box 32, then horizontally toward the center of the boiler, then vertically, then toward the rear to join 5 the mud drum below the downtake headers at some distance from the side of the boiler. Here also a great portion of tube is at a considerable distance from a straight line joining the ends of the tube with the results 10 above explained. The flexibility of tube 34 is greater than that of 39 because 34 does not lie in a single plane and considerable torsional flexibility is, therefore, present. This is also true of tube 22 and its 15 connections.

Many changes may be made in the form and arrangement of the apparatus and the various parts thereof without departing from the spirit of my invention.

20 I claim:

1. In combination, a boiler having horizontally inclined water tubes connected by water compartments, a water back in the furnace, a drip pan connected to the furnace 25 setting and located beneath one of the water compartments, and a pipe connecting the

water back with the water compartment, said pipe extending through an opening in said drip pan and being free to move vertically therein, said drip pan having a thimble loosely surrounding the pipe to prevent leakage of water from the pan through the opening for the pipe. 30

2. In combination, a boiler, a furnace therefor, a water back of relatively small 35 diameter in the furnace with its ends extending outside the furnace, a side wall water box of relatively small diameter located below the water back and extending through the front and the back of the setting, said water back and said water box each being provided with a domed projection adjacent each of the ends thereof, pipes connecting each end of the water back and the water box with the boiler water spaces, 40 45 said pipes being expanded into said projections, and said water back and said water box each having an opening at each end thereof, whereby they may be inspected throughout their length, and fittings for said 50 openings.

WILLIAM A. JONES.
